Attorney

UNITED STATES PATENT OFFICE.

GEORGE W. ERICSON, OF GALESBURG, ILLINOIS.

BASKET.

Application filed May 24, 1922. Serial No. 563,322.

To all whom it may concern:

Be it known that I, GEORGE W. ERICSON, a citizen of the United States, residing at Galesburg, in the county of Knox and State 5 of Illinois, have invented a new and useful Basket, of which the following is a specification.

The device forming the subject matter of this application is a basket of that general 10 type commonly used for containing pots of plants and the like, the basket comprising a ring, a bottom and staves, novel means being provided for maintaining the staves interlocked with the bottom and with the ring.

It is within the province of the disclosure 15 to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, with- 25 in the scope of what is claimed, changes in the precise embodiment of the invention shown can be made without departing from the spirit of the invention.

In the accompanying drawings:—

30 Figure 1 shows in plan, a device constructed in accordance with the invention; Figure 2 is an elevation; Figure 3 is a fragmental vertical section showing how the ring and the bottom are interlocked with the staves; 35 Figure 4 is a fragmental horizontal section showing how the staves are interengaged with the ring and with the bottom; Figure 5 is a fragmental section showing a modification.

40 The basket comprises an upper ring 1 which is T-shaped in cross section, the ring comprising a body 2 and a flange 3 projecting from the body, there being notches 4 in the outer edge of the flange 3. The bottom 45 of the basket may take the form of a spider 5, carrying a lower ring 6 constructed like the upper ring 1. The rings 1 and 6 are surrounded by staves 7 which are spaced apart circumferentially, the staves having 50 notches 8 receiving the flanges 3 of the rings

1 and 6, the staves fitting in the notches 4 of the said rings. The staves abut against the body portions 2 of the rings 1 and 6, as clearly shown in Figure 3 in connection with the ring 1. Owing to the way in which the 55 rings are interlocked with the staves, the staves cannot shift circumferentially of the rings, nor can the staves shift longitudinally. Bands 9, which may be made of strap metal, surround the staves 7 and hold 60 them interengaged with the rings, the bands being held by securing elements 10 to certain of the staves.

It is not necessary that strap metal bands be used. If desired, the band may be in the 65 form of a piece of wire 25 having its ends twisted together as at 26 in Figure 5, the twisted ends being located between certain of the staves 27, the wire being connected to any desired ones of the staves by staples 70 28 or the like.

What is claimed is:—

1. A basket of the sort described comprising a ring including a body and an outstanding flange, the flange having notches; staves 75 received in the notches, and having notches receiving the flange; and a band circumscribing the staves.

2. A basket of the class described comprising a ring including a body and an outstanding flange, the flange having notches; staves 80 disposed in the notches of the flange and having notches receiving the flange, the staves abutting against the body; and a band circumscribing the staves.

3. A basket of the sort described, comprising an upper ring including a body and an outstanding flange, and a bottom comprising a body and an outstanding flange, the flanges having notches; staves located in the 90 notches and provided with notches receiving the flanges of the bottom and of the ring; and a band circumscribing the staves.

In testimony that I claim the foregoing as my own, I have hereto affixed my signature 95 in the presence of two witnesses.

GEORGE W. ERICSON.
